UNITED STATES PATENT OFFICE.

LORENZO OLEA MORENO, OF NEW YORK, N. Y.

IMPROVED MEDICINE.

Specification forming part of Letters Patent No. 59,052, dated October 23, 1866

To all whom it may concern:

Be it known that I, LORENZO OLEA MORENO, of the city, county, and State of New York, have invented a new and Improved Medical Compound; and I do hereby declare that the following is a full, clear, and exact description thereof, which will enable others skilled in the art to make and use the same.

This invention relates to a simple and effective remedy for dysentery or diarrhea, which can be used with advantage by persons of both sexes and of every age, and which has proved very beneficial, particularly in such times when the cholera threatens to become epidemic.

My compound is made of calomel, extract of opium, powder of Peruvian coca, and gum-arabic, which ingredients are mixed together in about the following proportions: calomel, eighteen grains; extract of opium, two grains; Peruvian-coca powder, two grains; sirup of gum-arabic, two grains, from which mass, when well mixed, I produce six pills.

Mode of treatment.—First, for children until seven years of age, half a pill, which may be dissolved in a tea-spoonful of sirup; second, for a youth under twenty-one years of age, one pill; third, for a person over twenty-one years of age, two pills.

First day.—The pills should be taken between 3 and 4 o'clock a. m., on an empty stomach, and the patient should then remain quietly in bed for five hours, after which he must, if over twenty-one years of age, take two ounces of castor-oil mixed with hot or boiled milk and a lump of sugar; if a youth, one ounce, and if a child under seven, half an ounce. He should then rise at once and exercise within doors until the purge operates. A cup of hot and weak tea one hour after the purgative will be very beneficial, and in case of vomiting the purge it should be repeated as many as four times, in order to succeed in keeping one dose on the stomach. If by 6 o'clock p. m. the purgative should not have operated, a clyster of a little milk and a spoonful of the oil should be applied, and after it has produced the desired effect the patient should take his diet, once only, which should consist of a cup of well-boiled gruel, and, instead of common water, rice-water with gum-arabic.

Second day.—The patient should rest, and

take his diet three times—that is to say, at 8 a. m., at noon, and at 4 p. m.—a cup of well-boiled gruel, or of milk alone, and whenever thirsty, instead of common water, he may drink rice-water with gum-arabic. In case of fever or tenesmus, there should be given him this very day three semi-cupum baths, as hot as may be, of mallows and milk, so that he be covered from the umbilical region and half-way up the thigh. The bath should last from ten to twelve minutes, and then the patient should return to bed to perspire as much as possible.

Third day.—Between 3 and 4 o'clock a. m. the pills should be taken, and the mode of treatment on the first day should be repeated.

Fourth day.—The mode of treatment for the second day should be strictly followed.

Fifth day.—By this time it is more than probable that the patient will be free from all dangerous symptoms, such as continual and bad evacuations, fever, or tenesmus if he has had it. In this case, which is very general, the patient will only feel a debility or exhaustion of the stomach, and if so he will commence taking one of the tonic papers—one of the twelve in each package—and take one every three hours, dissolved in half a wine-glass of cold water, until he has taken three. This does not interfere with his taking his diet three times, nor his rice-water with powdered gum-arabic. He should continue taking said tonics for four days, and on the fifth day commence eating, at breakfast, sirloin or fillet of pork, half-broiled, and at dinner a soup made either of rice, bread, or vermicelli, and thus begin, little by little, to take more substantial food, until he is completely restored. During this time he should drink, instead of common water, that from which the natural cold has been removed by boiling or otherwise. Great care should be had in the choice of food in order not to fatigue the stomach, and the following diet should be kept for fifteen days: sirloin of pork, boiled eggs, chicken, bread soup, fillet of veal, and tea with or without milk.

Remarks.—If the sickness should be of a few days' duration, it is highly probable that with the first dose of pills, the purgative mentioned, and the aforesaid diet of gruel for four days, the patient will be radically cured; but if it

should be chronic and inveterate, accompanied with alarming symptoms, it may require not only the first but also the second and third doses, it being certain that with this treatment there is no dysentery nor diarrhea, however severe, which will not be cured.

In case that after the patient is cured he should have more than two evacuations per day, this would be nothing more than a slight derangement of the stomach, and in that case he should continue using the tonic powders, taking three papers per day, as before explained. If, on the contrary, the patient should remain costive, let him take on an empty stomach two ounces of castor-oil with milk and sugar; but it should be borne in mind that this purge should not be taken until four or five days have elapsed without an evacuation.

Females.—In case of pregnancy, the treatment should only be modified by diminishing the dose—one pill instead of two, and one ounce of castor-oil instead of two. Otherwise the mode of treatment is the same.

Notice.—The diet should be none other than boiled sago with milk, or milk alone.

If, owing to any imprudence, the patient should, after being cured, have a relapse, the pills should again be taken without loss of time.

N. B.—The rice-water for the patient should be made fresh every three hours, to prevent its becoming decomposed, and to every tumblerful a tea-spoonful of powdered gum-arabic should be added.

What I claim as new, and desire to secure by Letters Patent, is—

A medical compound made as and for the purpose described.

The above specification of my invention signed by me this 13th day of September, 1866.

DR. L. OLEA MORENO.
